UNITED STATES PATENT OFFICE

157,308

FABRIC

Phyllis Wayne, Los Angeles, Calif., assignor to
Harry Goldinger Textile Corporation, Los Angeles, Calif., a corporation of California

Application September 27, 1948, Serial No. 148,789

Term of patent 3½ years

(Cl. D92—1)

To all whom it may concern:

Be it known that I, Phyllis Wayne, a citizen of the United States of America and residing at Los Angeles, in the county of Los Angeles and State of California, have invented a new, original, and ornamental Design for Fabric, of which the following is a specification, reference being had to the accompanying drawing, forming a part thereof.

The figure is a face view of a piece of fabric showing my new design. A complete design unit is disclosed, which unit is repeated vertically and horizontally on the drawing.

I claim:

The ornamental design for a fabric, as shown and described.

PHYLLIS WAYNE.
